RADIO APPARATUS

Homer J. Loftis, Dayton, Ohio, assignor, by mesne assignments, to Radio Corporation of America, New York, N. Y., a corporation of Delaware

Application November 3, 1930, Serial No. 492,917

2 Claims. (Cl. 250—33)

This invention relates to an antenna circuit and in more particular to an antenna circuit for a remotely located radio receiver or the like.

In the installation of a radio receiver in apartment houses, sky-scrappers etc. it becomes necessary to have a very long lead-in that is a source of disturbance in the conventional antenna circuits, in that the long lead-in picks up local disturbing signals that are of such a magnitude that

10 their energy level is substantially equal to or even greater than that of the desired incoming signal.

An object of this invention is to reduce the undesirable disturbances usually local in source that are picked up by long lead-ins. This has been 15 accomplished by providing a step-down transformer near the aerial or the receiving portion of the antenna having the primary connected between the aerial and ground and the secondary to a transmission line that is connected to the 20 primary of a step-up transformer that has the secondary winding connected to the input terminals of the radio. This second transformer is located near the radio receiver so that undesirable 25 disturbances picked up by one side of the transmission line is substantially neutralized by the disturbances picked up by the other side of the transmission line.

In the present modification the volume enclosed by the antenna is comparatively small in 30 that the receiving portion or the aerial of the antenna is placed near the counterpoise which may be the roof of the building or a conductor supported in proper relation with respect to the aerial or the like. The transmission line transferring 35 the signal from the aerial to the radio receiver encloses a very small loop or volume in that the transmission line may be made from a pair of twisted conductors.

Further objects and advantages of the present 40 invention will be apparent from the following description, reference being had to the accompanying drawing wherein a preferred embodiment of one form of the present invention is clearly shown.

45 In the drawing:

In the single figure a schematic diagram of the antenna circuit has been shown.

In the drawing the reference character 10 indicates the receiving portion or the aerial of an 50 antenna mounted on top of a tall building or any other suitable place. It has one terminal 11 connected to the primary 12 of a step-down transformer 14. The primary of the transformer 14 has the other terminal 16 connected to the roof 55 or any other suitable counterpoise hereafter

called ground near the aerial 10 so that the loop formed by the aerial and the counterpoise or ground is very small. It can be readily seen that in large cities where there are numerous sources of disturbing signals, it is desirable to mount the 60 aerial 10 as far from the earth's surface as possible for the reason that disturbing signals diminish rapidly as the distance from the source increases.

A pair of transmission lines 18 and 20 connect the secondary 22 of the step-down transformer 65 14 to the primary 24 of a step-up transformer 26 having the secondary 28 connected to the antenna posts 30 and the ground post 32 of a radio receiver not disclosed. Both the primary and secondary windings of the step-down and step-up 70 transformers have their terminals grounded. In the single figure these terminals have been grounded at both ends of the transmission line. For certain installations it may be desirable to have them grounded at only one of the ends. It 75 has been found that a transmission line several hundred feet in length gives very good results when made according to this invention. Such a transmission line tends to neutralize the signals picked up by one line with the signals picked up 80 by the other thereby reducing undesirable disturbances.

While the form of embodiment of the present invention as herein disclosed, constitutes a preferred form, it is to be understood that other 85 forms might be adopted, all coming within the scope of the claims which follow.

What is claimed is as follows:

1. A radio energy interceptor arrangement for 90 remotely located radio receiving apparatus and the like comprising in combination, an aerial for receiving signal impulses, a counterpoise for said aerial and displaced therefrom only a comparatively short distance so that the path for transferring the charges of electrical energy between 95 the aerial and counterpoise is comparatively short, a step-down radio frequency transformer having its primary circuit in series with the aerial and counterpoise, a transmission line comprising a pair of twisted conductors, a step-up transformer 100 having its primary winding connected to the secondary winding of the step-down transformer through said transmission line and the secondary winding of said step-up transformer having its terminals connected to the input terminals of the radio receiver so that the voltage of the signal impulse is reduced while being transmitted over the transmission line and increased when transferred to the radio receiver, said transmission line 105 picking up equal disturbing voltage impulses that 110

tend to neutralize each other thereby reducing undesirable disturbances.

2. A radio energy interceptor arrangement for remotely located radio receiving apparatus and the like comprising in combination, an aerial, a counterpoise associated with the aerial and displaced therefrom only a comparatively short distance so that the path for transferring the charges of electrical energy between the aerial and counterpoise is comparatively short, a step-down transformer having one terminal of its primary winding connected to the aerial and the other terminal thereof connected to the counterpoise, a transmission line comprising a pair of

closely associated wires, in which one of said wires is grounded, a step-up transformer having its secondary winding connected to the input terminals of a radio receiver, said transmission line connecting the secondary winding of the step-down transformer to the primary winding of the step-up transformer whereby signal impulses picked up by the receiving portion of the antenna are transmitted to the receiver and whereby the voltage impulses picked up by one side of the transmission line are substantially neutralized by the impulses picked up by the other side of the transmission line.
